(57) **CLAIM**

An adapter mount, as shown and described.

DESCRIPTION

FIG. 1 is a top perspective view of our new design of an adapter mount;

FIG. 2 is a bottom perspective view thereof;

FIG. 3 is a top view thereof;

FIG. 4 is a bottom view thereof; and,

FIG. 5 is a side view thereof.

The broken lines in the above described FIGS. 1-5 are for illustrative purposes only, depict environmental matter, and form no part of the claimed design.

1 Claim, 5 Drawing Sheets(56)
